UNITED STATES PATENT OFFICE

2,192,158

POSE REFLECTING SYSTEM

Luther G. Simjian, New Haven, Conn., assignor
to The Reflectone Corporation, Stamford,
Conn., a corporation of Connecticut

Application October 14, 1936, Serial No. 105,451

4 Claims. (Cl. 88—74)

This invention relates to pose or image observing devices designed so that the observer may obtain, while seated in front of one mirror, rear, side and profile views with the aid of an auxiliary revoluble mirror which may be readily moved by the observer and which is maintained automatically at the correct angle for the observer to see herself from various angles without doing more than slightly turning the head.

10. A further object is to simplify apparatus of this character to reduce the cost and improve the appearance to make it available for beauty parlors, barber shops, modiste shops, etc.

Other objects of the invention will become apparent from the appended claims and from the following description of some of the structural forms my invention may assume, but it will be understood that this description is illustrative only, and that the scope of my invention is limited only by the scope of the claims.

Referring to the drawings:

Fig. 1 is a side elevation, partly in section, of the preferred form of my invention.

Fig. 2 is a top plan view of the same, showing the movable mirror in different positions.

Fig. 3 is a bottom plan view of the bracket that supports the same, showing the stops thereon.

Fig. 4 is a vertical section through the supporting standard, with the observer's seat.

30. Fig. 5 is a diagrammatic view showing the operating belts for the device.

Fig. 6 is a side elevation of a modified form of the device.

Fig. 7 is a vertical section of the lower portion of the upright which supports the moving mirror.

Fig. 8 is a detail of the stop pins on the rotatable arm supporting the moving mirror.

According to one form of my invention the poser sits on chair 1, which as shown in Figs. 1 and 2 is fixedly mounted on post or shaft 2 secured in base 3. Under the chair seat is rotatably mounted a hand wheel 50 or other manual means for rotating the movable mirror 4. Said wheel is secured to a sleeve 5 journaled at 6 and 7 on rod or post 2 and having a rearwardly extending hollow arm 8 carrying at its outer end hollow upright member 9, within which the stem 10 supporting mirror 4 is journaled on a vertical axis. As shown particularly well in Fig. 7, said stem is journaled in ball bearings 11 and 12 within sleeve 13 threaded at the bottom within a collar 14 extending upwardly from arm 8, the bearings being spaced by sleeve 15. Preferably the mirror stem is in two parts, a lower part 10 and an upper part 16 which is detachably se-

cured to the top of part 10. Part 16 is shown as swaged at its lower end in a cap 17 which is detachably connected as by means of set screws 18 to a nut 19 threaded on the top of stem 10. Both the sleeve and cap may be covered by ornamental covers 20 and 21. Preferably, the upper stem 16 is bent rearwardly to form a goose neck, to the upper end of which the frame of mirror 4 is secured. The mirror thus lies well to the rear of the observer's head and is revolved about 10 shaft 2 as a center, which lies approximately in the same vertical line as the poser's face.

In order to keep the mirror at the correct angle as it is moved from one position to another, as indicated in Fig. 2, I provide a metallic belt 15 or chain 22 which has a non-slip engagement with a pulley 23 on stem 10, and also a non-slip engagement with the stationary post 2. For this purpose, I prefer to use a steel belt riveted at points 24 and 25 to post 2 and stem 10, respectively. The relative size of pulley 23 with respect to post 2 is chosen so that as mirror 4 is revolved about the post, it will also be rotated with stems 10 and 16 substantially about the virtual image as a center as seen in the large stationary mirror 32. To limit the revolution of arm 8, said arm is shown as provided with a pair of short posts 26 and 27, preferably rubber covered and adapted to engage lugs 28 and 29 on the metal frame 30 to which the chair bottom is secured.

Additional or alternative manual means may also be provided. One such means comprises a hand crank 31 rotatably mounted in front of mirror 32 (see Fig. 1). Said crank is shown as 35 secured to a vertical shaft 33 journaled in brackets 34 and 35 and extends through a slot in shelf 51 in front of mirror 32. Said shaft carries at its lower end a sprocket 36 connected by chain 37 to a sprocket wheel 38 to sleeve 5, so that 40 the mirror 4 may be revolved. To this end, sleeve 5 is shown as having a downward extension 39 which passes through a slot 40 in the base and has said sprocket wheel 38 secured thereto.

It is obvious that my invention may assume different forms, a modification thereof being illustrated in Fig. 6. In this form, the observer sits or stands in front of the main mirror 32, and the support for the auxiliary mirror 4 and the mechanism for turning it are carried overhead. In this case, the vertical crank shaft 33' is connected through a sprocket chain 40 to a sleeve 41 rotatably mounted on stud 42, fixedly mounted in a bracket 43 extending laterally from the wall 44. To said sleeve is secured an arm 8' 45

corresponding to arm 8, in which is journaled shaft 10' carrying the mirror rod 16' and mirror 4', as before, except in an inverted position. To take the strain of the weight of arm 8' off stud 42, a roller may be journaled on a rear extension thereof which rolls on an inverted trackway 53. Mirror 4' is turned through the proper angle as it is revolved by a band 22' passing around and secured to fixed stud 42 and shaft 10', as before.

It should be noted that the arc through which the mirror 4 revolves is of less radius than the distance between the two mirrors 4 and 32, or, in other words, that the center of revolution of the arm 8 is located between said mirrors. This has the advantage over prior systems of this character that the mirror 4 is bodily moved through a less distance than where its radius of movement is great, so that the mirror 32 may be made of less width than otherwise.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Thus, it is obvious that the mirror 4 may be moved by means other than direct manual power, such as electrical means, if desired, as shown in my copending application Serial No. 93,343, for Pose reflecting apparatus, filed July 30, 1936.

Having described my invention, what I claim and desire to secure by Letters Patent is:

1. In a pose reflecting device, a primary mirror which the poser normally faces, a secondary mirror, means for revolvably mounting the latter for turning movement about a substantially-vertical axis to be oriented behind the poser, manually operable means adjacent said secondary mirror for so revolving said secondary mirror, and means for rotating said secondary mirror about a second axis as it is revolved to change its angular position about both axes, so constructed and arranged that the poser's image reflected therefrom remains visible in the primary mirror, said means including a band having two flexible reaches and anchored at one end around a fixed part of one diameter adjacent said first axis and at the other end around a part of greater diameter connected to said secondary mirror.

2. In a pose reflecting system, a fixed mirror, a spaced revoluble mirror, an arm on which said second mirror is pivotally mounted, a fixed pivot shaft on which said arm is pivotally mounted, a handle in front of the poser, gear means rotatably mounted on said shaft and turned from said handle, said arm being secured to said gear means to revolve therewith, and a flexible band anchored at one end around a part on said shaft of one diameter and another a part connected to the mirror of a greater diameter, the

ratio of said diameters being such as to maintain the mirror at the proper angle as the arm is revolved.

3. In a pose-reflecting device, the combination with an observing-mirror; of a pose-casting mirror; two support-members concentrically-arranged intermediate said mirrors, one being a fixed vertical member, and the other being a mirror-swinging member rotatable relatively thereto about a vertical axis; a radial-member 10 carried by and rotatable with said mirror-swinging member; a vertically-extending mirror-shifting member rotatably carried at the free end of said radial-member and having said pose-casting mirror secured thereto; turning-means connected to and operable to turn said mirror-swinging member to cause said pose-casting mirror to swing about an axis intermediate the said mirrors and about a radius substantially less than the distance therebetween; and automatically-operable shifting-means connected to said fixed support-member and to said mirror-shifting member and responsive to turning movements of the mirror-swinging means to rotate said mirror-shifting member and cause said pose-casting mirror to shift about the vertical axis of the last-named member simultaneous with swinging movement thereof.

4. In a pose-reflecting device, the combination with an observing-mirror; of a pose-casting mirror; two support-members concentrically-arranged intermediate said mirrors, one being a fixed vertical member, and the other being a mirror-swinging member rotatable relatively thereto about a vertical axis; a radial-member carried by and rotatable with said mirror-swinging member; a vertically-extending mirror-shifting member rotatably carried at the free end of said radial-member and having said pose-casting mirror secured thereto; turning-means connected to and operable to turn said mirror-swinging member to cause said pose-casting mirror to swing about an axis intermediate the said mirrors and about a radius substantially less than the distance therebetween; and automatically-operable shifting-means connected to said fixed support-member and to said mirror-shifting member and responsive to turning movements of the mirror-swinging means to rotate said mirror-shifting member and cause said pose-casting mirror to shift about the vertical axis of the last-named member simultaneous with swinging movement thereof; the mirror-swinging means and the mirror-shifting means being arranged in predetermined relationship to secure a selected angular movement of the pose-casting mirror about the relatively-adjacently located vertical axis of said mirror-shifting member, relatively to simultaneous angular movement thereof about the relatively-distantly located vertical axis of the mirror-swinging member.

LUTHER G. SIMJIAN.
